UNITED STATES PATENT OFFICE.

SAMUEL J. WENTWORTH, OF NEWPORT, KENTUCKY, ASSIGNOR, BY MESNE ASSIGNMENTS, TO UNITED SHOE MACHINERY COMPANY, OF PATERSON, NEW JERSEY, A CORPORATION OF NEW JERSEY.

SHOE-FINISHING MACHINE.

1,010,550.

Specification of Letters Patent.

Patented Dec. 5, 1911.

Application filed June 21, 1905. Serial No. 268,280.

To all whom it may concern:

Be it known that I, SAMUEL J. WENTWORTH, a citizen of the United States, residing at Newport, in the county of Campbell & State of Kentucky, have invented certain new and useful Improvements in Shoe-Finishing Machines, of which the following is a specification.

This invention relates to machines for finishing shoes and is herein shown as embodied in a machine for shrinking and ironing the uppers of lasted shoes to perfect the appearance of the surface of the stock and to take out, by smoothing and rubbing and by the shrinking effect of heat, fullness of stock or even wrinkles which may remain in the shoe when it comes to this finishing operation.

An important feature of this invention is to be recognized in a working tool provided with an edge shaped and arranged to engage the shoe upper in the crease between the last and the sole edge and a face shaped to engage the upper on the side of the last 25 above said crease and means for actuating said tool lengthwise of the crease to shape said engaged portions of the upper to the underlying faces of the last and the edge of the shoe innersole. This feature of the invention is preferably embodied in a tool having a concave face to engage the upper on the side of the last and a blunt edged flange in continuation of said face to extend into the crease between the sole and upper 35 and to be held away from the sole and upper connecting seam so as to prevent injury to said seam by such engagement with the side of the shoe, and means is preferably provided for actuating the tool in a direction appropriate to give a rubbing treatment to the work. By such a tool so actuated these portions of a shoe can be shaped with accuracy and rapidity and the rubbing action as the work progresses sets the stock in 45 the shape it acquires. In accordance with a further feature of this invention I employ as such tool a heated upper shaping roll formed with an annular concave ironing surface in its periphery shaped to receive the 50 convex surface of the toe portion of a shoe said concave surface of the roll terminating at one end of the roll in an overhanging smooth faced lip to enter the welt crease of the shoe. This contour is of importance for

it enables one to reach into the welt crease 55 and finish the surface of the upper as far as the upper will be visible in the completed shoe. The work of such an instrument, when heated, is of particular value because it is about the curved edge of the shoe bottom at 60 the toe that it is most difficult to last the shoe without leaving wrinkles that extend far enough outwardly to be visible in and above the welt crease.

I have discovered that the shrinking effect 65 of heat on upper leather of dry tannage is very marked and that by the use of the present apparatus I am enabled very rapidly to improve the appearance of shoes, particularly about the toe and in the welt creases, 70 without any injurious results to the upper leather and thereby either to obtain a better product or an equal product at a less expense for careful workmanship in lasting. I have also discovered that by the use on the leather 75 of a viscous material like vaseline, for example, I am enabled to employ with safety a tool that is heated to a higher temperature than can otherwise be employed, thereby enabling me to shrink the leather to a greater 80 extent or more rapidly than can be done without such material. Also the use of such viscous material enables me to treat enameled leather the coatings of which are softened by the heat and would adhere to 85 the bare tool. A further feature of this invention is therefore to be recognized in means for applying viscous material to a heated roll and driving the roll to rub and heat the upper and to distribute the viscous 90 material automatically over the surface of the upper engaged by the roll. The roll may advantageously be formed with an ironing surface that is extended from the concave 95 annular surface above described into a convex annular portion shaped to treat the top face of the shoe, so that the several parts of the toe, likely to require treatment, can be operated upon conveniently with one handling of the shoe. The described tool has 100 the advantage that the double curvature formed by the two adjacent faces gives a contour, one portion or another of which is adapted to almost every part of the shoe 105 that is to be worked upon.

A further feature of this invention which is of practical importance is found in the provision for heating the working surfaces

of the roll. These surfaces, as above described, are mainly on the periphery of the roll and they must be kept smoothly polished and of constant shape. I have provided a heating means which is devoid of the usual objections to gas flames and steam heaters, both of which require outside sources of supply and also produce discomfort to the workman in warm weather, and which will adequately heat to the desired degree the peripheral working faces of the tool without injuring them. To this end I have formed the rotary tool with a non-working end face against which is arranged for frictional engagement a wooden block adjustably supported in a holder to engage said end face adjacent to the periphery of the tool and preferably adjacent to that one of the peripheral working faces which it is most important to heat to the highest temperature. A particular advantage for this heating means is found when the ironing roll is coated with viscous material as contemplated by this invention because it heats the roll without danger of igniting such material or of rubbing it off.

The several features of this invention will be more fully understood from the following description of the illustrative embodiment herein presented and will then be pointed out in the claims.

Figure 1 is a left hand end elevation of the machine; Fig. 2 is a top plan view; Fig. 3 is a right hand elevation of the friction heating pin support; Fig. 4 is an enlarged elevation of the rotary shrinking and ironing roll and the heating device, showing the engagement of the latter with a non-working end face of the roll near the peripheral face which is used for rubbing and shrinking the stock in the welt crease; Fig. 5 shows another desirable shape of ironing roll from that shown in Fig. 2.

The machine is shown as a bench machine although it might obviously be mounted on a pedestal instead of the base plate 1 from which rises the arms 2 that provide bearings 3 for shaft 4. The shaft has fast and loose pulleys 5 and 6 and projects at the left hand end beyond the bearings to support the tool A which is a roll. This mounting gives freedom for presentation of the shoe to the different portions of the roll and for manipulation of the shoe as may be required to obtain treatment of the several portions of the upper that need smoothing and shrinking. The peripheral working faces of the roll comprise an annular concave ironing surface near the right hand end of the roll shaped to receive the convex surface of a shoe toe and terminating at the right hand edge in an overhanging smooth faced lip or edge a, shaped and arranged to engage the shoe upper in the crease between the last and the sole edge as indicated by

dotted lines in Fig. 2. The roll also has a further ironing face extended at the left hand side of the concave portion into a convex portion shaped to treat the top face of the shoe between the instep and the toe 70 where the upper tends to bridge and frequently needs to be shrunk to fit it down to the contour of the last. It is to be noted that when the work is presented as in Fig. 2 the tool is actuated lengthwise of the welt 75 crease to shape uniformly all around the toe the engaged portions of the upper to the underlying faces of the last and the edge of the innersole.

In the arms 2 near the base 1 are bearings 7 for a rod 8 on the left hand end of which is an arm 9 curved upwardly to and terminating in a substantially horizontal portion on the rear side of the roll A. In this front face of this upper end of the arm 9 85 is a seat for a block of felt 11 or the like the front edge of which is shaped in accordance with the contour of the roll A. Above the block of felt is a receptacle 10 for viscous material such as thin vaseline or oil 90 which through a suitable duct flows or is pressed down to saturate the felt and cause the latter to keep the roll coated with the viscous material which is thus automatically distributed over the surfaces of the upper 95 that are engaged by the roll. As will now be described, the roll is heated and not only does the heat assist in producing the flow of the viscous material from the receptacle to the felt block but it causes the vaseline 100 or oil to be applied in a heated condition to the stock into the surface of which it is worked by the rubbing action of the roll. If enameled leathers are being treated the vaseline is distributed over the enamel coating and prevents it from adhering to the heated roll. In all cases the vaseline is a protection to the leather from injury by the heat from the roll. A screw 12 furnishes means to secure the block 11 in contact with 110 the roll A.

A bracket d forms a bearing opposite the right hand end face of the roll A and near its periphery for a screw b, Fig. 4. The left hand portion of this screw is tubular 115 and contains a wooden pin C which projects therefrom into engagement with a non-working end face portion of the roll. The screw and bracket furnish means for holding the pin in adjustable frictional engagement with the roll and causing the latter to be heated, the heat being developed adjacent to the working face of the roll.

The form of iron shown in Fig. 2 is adapted to shrink and smooth the toe and 120 shank, as well as the toe portion of the shoe below the instep. The workman when finishing the toe applies it to the iron in position shown by dotted lines in Fig. 2 and moving the shoe back and forth, pressing it 130

to the action of the tool, around the shank as well as the toe portion of the shoe. Frequently the wrinkles extend across the top face of the shoe, or vamp portion of the shoe, in which event the convex portion of the iron is adapted to smooth out the wrinkles therein. In turn shoes wrinkles are more apt to occur in the vamp portion than with welt shoes and for this purpose the 10 extended portion of the iron shown in Fig. 2 is highly desirable. In turn shoes the iron is applied to the shoe after it has been turned and placed on the last, and after the heel seat is fastened by the laster. In other 15 than turned work the iron shown in Fig. 5 has been found sufficient to finish and complete the lasting of the shoe, making a complete and smooth fit of the upper.

Having explained the nature of this invention and described a preferred embodiment thereof, I claim as new and desire to secure by Letters Patent of the United States:—

1. In a machine for shrinking and ironing the uppers of lasted shoes, a heated ironing roll formed with an annular concave ironing surface in its periphery shaped to receive the convex surface of a shoe toe and terminating at one end of the roll in an overhanging smooth faced lip to enter the welt crease.

2. In a machine for shrinking and ironing the uppers of lasted shoes, a heated ironing roll formed with an annular concave ironing surface in its periphery shaped to receive the convex surface of a shoe toe and terminating at one end of the roll in an overhanging smooth faced lip to enter the welt crease, said ironing surface being extended at the other side of the concave portion into a convex annular portion shaped to treat the top face of the shoe.

3. A machine for shrinking and ironing the upper of a lasted shoe, having in combination, a heated ironing roll shaped to treat different portions of the upper of the shoe, means for applying viscous material to the heated roll, and means for driving the roll to rub and heat the upper and automatically to distribute the viscous material over the surface of the upper engaged by the roll to prevent injury to the leather by the heated roll.

4. A machine for finishing the uppers of shoes, having in combination, a rotating upper ironing tool having a peripheral work rubbing face, a stationary bearing in which said tool is mounted, means for actuating

said tool, and means for heating the tool comprising a wooden block, a support for holding said block in position to engage a non-working end face of the tool near to the said peripheral working face, and an adjusting device co-operating with the block and said support for adjustably forcing the block into frictional engagement with said non-working end face of the ironing tool for heating said peripheral work rubbing face.

5. A machine for finishing the uppers of shoes, having in combination, a working tool provided with an edge shaped and arranged to engage the shoe upper in the crease between the last and the sole edge, and a face shaped to engage the upper on the side of the last above said crease, and means for actuating said tool lengthwise of the crease to shape said engaged portions of the upper to the underlying faces of the last and the edge of the shoe innersole.

6. A machine for shrinking and ironing the upper of a lasted shoe, having in combination, a heated roll provided with a concave work rubbing face to act on the upper on the side of the shoe, said face terminating at one end in a blunt edge flange formed and arranged to rub the upper in the crease between the projecting edge of the sole and the side of the last and to be held away from the inseam stitches of the shoe by the first mentioned face, a fixed support in which said roll is journaled and means to drive said roll to iron and shrink to the underlying faces of the last and the shoe innersole, by friction and heat, the engaged faces of a shoe presented and advanced relatively thereto in the hands of the operator.

7. In a machine for finishing shoes, the combination with a stationary support, and means mounted thereon that is constructed and arranged with a concave face to engage the upper on the side of the shoe, and a blunt edged flange in continuation of said face to extend into the crease between the sole and upper and to be held away from the sole-and-upper-connecting seam by such engagement with the upper, of means for actuating said engaging means to rub the shoe, substantially as described.

In testimony whereof, I have hereunto set my hand.

SAMUEL J. WENTWORTH.
